UNITED STATES PATENT OFFICE.

LYDIA ADELLA CRAVEN, OF SPOKANE, WASHINGTON.

DESIGN FOR A DRESS-SHIELD SAFETY-PIN.

SPECIFICATION forming part of Design No. 33,046, dated August 7, 1900.

Application filed April 3, 1900. Serial No. 11,387. Term of patent 14 years.

To all whom it may concern:

Be it known that I, LYDIA ADELLA CRAVEN, a citizen of the United States, residing at Spokane, in the county of Spokane and State 5 of Washington, have invented a new and original Design for Dress-Shield Safety-Pins, of which the following is a specification.

My invention relates to a new and original design for a dress-shield safety-pin.

10 The accompanying drawing is a view in perspective of my new and original design for a dress-shield safety-pin.

As shown in the accompanying drawing, A represents the pin proper, and B is the back 15 or body portion, which constitutes the leading feature of my design. This back or body portion is in the form of a continuous unbroken arch which extends from one end to the other

of the pin A. The back or body portion is connected at one end to an end of the pin by 20 means of the coil 1, and the other end has the hook-shaped clasp 2 to receive and hold the point of the pin when the pin is closed.

Having fully described my invention, what I claim as new, and desire to secure by Letters 25 Patent, is as follows:

The design for a dress-shield safety-pin, substantially as shown and described.

In testimony whereof I have signed my name to this specification in the presence of 30 two subscribing witnesses.

LYDIA ADELLA CRAVEN.
